Primary Examiner — L. A. Grabenstetter

(57) **CLAIM**

The ornamental design for a phone case, as shown and described.

DESCRIPTION

FIG. 1 is a front perspective view of phone case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its state diagram thereof;

FIG. 10 is an enlarged detail view of area 10 in FIG. 2; and, FIG. 11 is an enlarged detail view of area 11 in FIG. 4.

The broken lines in the drawings illustrate the portions of the phone case which form no part of the claimed design.

The long dash-short dash broken lines in FIGS. 2, 4, 10 and 11 show the boundaries of the enlargements shown in FIGS. 10 and 11, and form no part of the claimed design.

1 Claim, 11 Drawing Sheets
